CLAIM

The ornamental design for a grinder bistrique, as shown and described.

DESCRIPTION

FIG. 1 is a front elevational view of a grinder bistrique, showing our new design; the rear, left side and right side elevational views are a mirror view of FIG. 1;
 FIG. 2 is a top plan view thereof;
 FIG. 3 is a bottom plan view thereof;
 FIG. 4 is an enlarged view of a part of FIG. 1;
 FIG. 5 is an enlarged view of FIG. 2; and,
 FIG. 6 is an enlarged view of FIG. 3.

1 Claim, 5 Drawing Sheets
